UNITED STATES PATENT OFFICE.

NORRIS ELMORE CLARK, OF PLAINVILLE, CONNECTICUT.

CORNER-BEAD MANUFACTURE.

1,142,494.

Specification of Letters Patent. Patented June 8, 1915.

Application filed December 12, 1914. Serial No. 876,773.

To all whom it may concern:

Be it known that I, NORRIS ELMORE CLARK, a citizen of the United States of America, and residing at Plainville, in the county of 5 Hartford and State of Connecticut, have invented new and useful Improvements in Corner-Bead Manufacture, of which the following is a specification.

My invention relates not only to an improved corner bead construction but to the 10 method of manufacture and a machine for carrying out this method automatically.

It is my main object to make a bead which is relatively cheap but strong and which 15 will afford a satisfactory key for the plaster.

The bead has plaster-receiving openings 20 in each side. These openings are preferably formed by simply slitting the metal and turning the edges of the slits so as to constitute reinforcing flanges instead of by punching and removing portions as has been customary. Preferably there are a plurality of 25 rows of these openings in each side of the bead with longitudinal ribs constituting reinforcing members between the rows. The 30 edges of the openings are preferably turned under so as to provide under-cut key-ways for securely anchoring the plaster. I also prefer to stagger the openings on each side 35 so as to better distribute the keying effect. The preferred construction has what is termed a "bull nose" or flanged edge. On account of the disadvantages of hot or electro galvanizing or sherardizing I may provide a pure zinc protecting edge mechanically applied.

The construction above outlined particularly lends itself to manufacture by a continuous process in a single machine receiving 40 the blank sheet or strip at one end and delivering the finished product. The machine in its simplest form consists of a plurality of sets of rolls with connecting guides and gages when desired whereby a sheet may be 45 cut into strips and each strip first slit, the edges of the slits flanged to form openings and to reinforce the sides, the strip then gradually bent adjacent the center by raising the center and depressing the edges, 50 bending or turning under the edges of the flanges of the openings, contracting the sides adjacent the center to start the edge flange or the bull nose, continuing the drawing in of the sides and finishing the bull 55 nose and then straightening the bead if nec-

essary. The zinc protecting ribbon may be attached by running it into the machine after the holes have been formed, then tucking portions of the edges of the ribbon into the openings and then folding the edges under. From this point all the operation is the same with or without the zinc edge. The formation of the bead with the zinc edge on it stretches the zinc and draws it smoothly.

The holes in the sides may be arranged in 60 a number of different ways and the flanges and corrugations may be varied.

Figure 1, is a side view showing a train of 65 rolls and guides for carrying out the complete process of manufacture. Fig. 2, is a 70 fragmentary view of a piece of stock showing the cutting of it into two strips and the successive slitting and formation of the openings and longitudinal ribs. Fig. 3, shows a side view and an end view of a 75 fragment of the preferred form of the completed product with the openings staggered and the flanges turned inward. Fig. 4, shows a fragmentary side and an end view of a modification of the product with the 80 openings on each side arranged side by side. Fig. 5, shows a fragmentary side view and an end of another modification of the product with the flanges turned outward. Fig. 6, is an end view of another modification 85 of the product. Fig. 7, shows an end and side view of another modification of the product with only one rib and two rows of 90 openings in each side. Fig. 8, shows an end view and a side view of another modification 95 of the product. Fig. 9, is a fragmentary view of the infeeding and edge smoothing rolls. Fig. 10, is a fragmentary sectional view of the slitting rolls and showing diagrammatically the product as affected thereby. Fig. 11, is a fragmentary sectional view of the corrugating and hole opening rolls and showing diagrammatically the product as affected thereby. Fig. 11^a is a 100 sectional view of the zinc guide. Fig. 12, 100 is a fragmentary sectional view of the zinc tucking rolls and showing diagrammatically the product as affected thereby. Fig. 13, is a fragmentary sectional view of the zinc 105 folding rolls and showing diagrammatically the product as affected thereby. Fig. 14, is a fragmentary sectional view of the first pair of bead forming rolls and showing diagrammatically the product as affected thereby. Fig. 15, is a fragmentary sectional view 110

of the second pair of bead forming rolls and showing diagrammatically the product as affected thereby. Fig. 16, is a fragmentary sectional view of the third pair of bead forming rolls and showing diagrammatically the product as affected thereby. Fig. 17, is a fragmentary sectional view of the first set of bull nose forming rolls and showing diagrammatically the product as affected thereby. Fig. 18, is a fragmentary sectional view of the second set of bull nose forming rolls and showing diagrammatically the product as affected thereby. Fig. 19, is a fragmentary sectional view of the final set of bull nose forming rolls and showing diagrammatically the product as affected thereby.

The product consists of the bead proper, corner member or front edge 1 and two sides which flare outwardly therefrom. The rear edges 2 of the sides in the form shown are continuous. Three rows of openings 3, 3', 3'' are provided in each side. The rear edge 4 of each opening 3 of the outer row is flanged inward and under so as to afford a key-way for the plaster and to reinforce the side. Similarly the front edge 4' of each of the openings 3' in the rear row is bent inward and turned under. Similarly both edges 4'' of each opening of the central row are bent inward and turned under. The flanges 4, 4' and 4'' are turned inward in such a way as to provide ribs 5, 5' extending longitudinally of the sides between the rows 35 of openings. These ribs reinforce the sides materially and make it possible to use a much lighter gage of metal than would otherwise be desirable. As the openings are formed by displacing the metal in such a 40 way as to reinforce the sides, the bead for a given gage of metal is much stronger than where the metal is removed as is the customary practice. In the preferred form the bead proper is provided with lateral flanges 45 or shoulders 6, 6' of the bull nose type which is found more desirable in a construction of this character. The rear edges are preferably provided with holes such as 7 for attaching nails or wires. The exposed edge or 50 the nose of the bead may be protected by means of a strip or ribbon 8 of suitable material such as pure zinc.

A plurality of beads may be formed simultaneously by trains of rolls appropriately arranged but it will be necessary to describe only the formation and operation on a single strip. The stock 10 may be of a width to form one or more beads. In the present instance in Fig. 2, the stock is of the width of 60 two beads and is divided along the line 11 into two strips. The stock of each strip is slotted along each side of its center line as at 12, 12' and 12'' in staggered arrangement, and the slits on opposite sides of the center line being relatively staggered. The edges

13, 13' and 13'' of these slits are flanged or bent down substantially at right angles to the plane of the strip. At the same time the metal at 14, 14' and 14'' is inclined in the same general direction so as to facilitate the flanging action and complete the formation of the ribs 5, 5'. Afterward the flanges 13, 13', 13'' are bent under as at 4, 4' and 4'' respectively to improve the keying effect in the plaster.

Close to and on each side of the center line the strip is slightly corrugated, grooved or bent along the lines 15 which ultimately form the shoulders or side edges 6, 6'.

The rolls 16 feed the stock into the machine and the grooved rolls or disks 17 guide it and smooth the stock at the edges. The disks 18 and 18' acting in conjunction with the disks 19, 19' and 20, 20' serve to form the slits 12, 12 on opposite sides of the center line of the strip as the stock passes through. The slits 12' are formed by the coöperation of the disks 21, 21' and 22, 22'. The slits 12'' are formed by the coöperation of the disks 19, 19' and 22, 22'. It will be noted in Fig. 10 that in forming the outer row of slits the edges are somewhat depressed from the plane of the metal between the slits 12' and 12'' and similarly the metal between the rows of slits 12 and 12'' is somewhat depressed. This action facilitates the cutting as well as the subsequent ribbing.

Rolls 24 and 24' serve to open up the slits and form the ribs in the sides of the strip as well as to form nail holes in the edges. The slits are opened by projections 25, 25' and 25'' carried by the upper roll 24. The lower roll 24' is cut away to admit of the flanging of the strip. The lower roll is provided with projections 26, 26' which coöperate with the projections 25, 25' and 25'' in forming the ribs, the upper roll being cut away to correspond therewith making due allowance for the thickness of the metal at the ribs. The upper roll is provided with projections 27 for assisting in forming the trough-like portion 14''. The edge holes 7 are formed by prongs 28 carried by the upper roll and coacting with recesses 28' in the lower roll. These prongs carry the metal down as at 29.

Lateral guide rolls such as 30 may be provided for the edges of the stock between adjacent pairs of rolls at such points as may be found desirable. Lubricant may be admitted to the guides, cutters or formers at such points as may be necessary by means of a tube or pipe such as 31. Upper and lower guides 32 and 32' may be provided between the adjacent pairs of rolls for directing the stock. These guides may have rails corresponding with the position of the annular projections 26, 26' to guide the ribs of the stock between subsequent pairs of rolls.

The rolls 34, 34' are provided with projections such as 36 corresponding with the

inner rows of openings for tucking portions 37 of the edges of the zinc ribbon 38 through the openings as shown in Fig. 12, the roll 34' being provided with suitable recesses to 5 allow for the same. The zinc ribbon may be introduced through a guide 38'. The rolls 39, 39' serve to bend or fold under the edges of the zinc ribbon as shown at 37'. This folding is affected by projections 40 on roll 39' cooperating with shoulders and recesses 10 in the roll 39.

The zinc may be preliminarily flanged somewhat by suitable rolls or by drawing it through a suitably shaped guide as indicated in Fig. 11^a so that it will conform better to the stock where the tucking is to be effected.

Rolls 42, 42' serve to start the formation of the bead proper, being provided with a 20 groove 43 and a projection 43' respectively which interfit and bend the strip along the lines 15, 15. The roll 42' also carries projections 44 for entering the edge holes 7 and spreading the prongs 29 against the under 25 side of the stock as shown at 29' Fig. 14, the upper roll 42 having recesses 44' to correspond therewith.

Rolls 46, 46' have a central groove and 30 projection 47 and 47' respectively for continuing the formation of the bead proper. The lower roll also has inclined shoulders 48, 48' for bending the flanges 13 and 13' respectively to the position shown at 4, 4' in Fig. 15. The lower roll is provided with 35 inclined shoulders 48'' for bending the flanges 13'' in the position shown at 4'' in Fig. 15, the upper roll being provided with walls 49, 49 for holding the stock down. These rolls 46, 46' not only gradually form 40 the bead proper, but draw the sides inwardly somewhat as shown by the comparison between Figs. 14 and 15.

Rolls 51, 51' are shaped in cross section to continue the formation of the bead proper 45 and drawing in the sides as shown in Fig. 16. Rolls 46, 46' or the rolls 51, 51' or both sets of rolls may be adjusted so as to assist in completely flattening the prongs 29'.

The roll 53 has a fin 54 which projects 50 into the inside of the bead and supports it against the pressure of the upper roll 53'. The rolls 55, 55 press inward the sides of the bead immediately below its edge as 55 shown in Fig. 17, the lower edges of the sides of the bead being left somewhat free to move.

The roll 57 serves to support the sides of the bead while the lateral rolls 58, 58 continue to bend the sides inward so as to substantially close them. The upper roll 57' holds the upper edge of the bead in position 60 and assists in giving it its proper shape.

The lower roll 60 continues the support of the sides of the bead while the rolls 61, 61 complete the formation of the sides and

edge of the bead proper. This lower roll may be stationary or it may be made a mere stationary guide.

The stock is preferably treated by a plurality of such rolls as 61 in order to properly finish the bead. All of the rolls may be driven or only such rolls as it is necessary to drive in order to keep the stock moving through the machine and deliver it finally. All or part of the rolls may be provided 70 with means for adjustment or spring pressure devices as is common in the metal working art.

It will be noted that the shape of the co-operating guide 60 and roll 61 is such as to 80 cause the edges of the product to flare outwardly at substantially 90° to each other. By varying the proportions and arrangement of the guide 60 and the rolls 61, a bead otherwise the same, may be given different 85 heights to correspond with different grounds or thicknesses of plaster. The desired result may be obtained by simply substituting the proper rolls and guide. The same rolls may be used even if the stock varies some- 90 what in thickness.

By retaining the ribs in what may be termed their open position throughout the first part of the machine the stock may be 95 readily and accurately guided and held until the central bead is started. After this the central bead channel serves to guide the stock until it reaches the finishing rolls which deliver it from the machine. It is therefore possible to handle somewhat narrower or wider stock in the same machine by suitably adjusting the introductory guides.

In the modified form of product shown 100 in Fig. 4, the openings 65 in the side are not staggered but are arranged side by side. The openings on the two sides however are staggered relative to each other. In this figure the flanges 66 are shown substantially at right angles to the plane of the side and 110 the flanges 67 are shown closed toward each other so as to provide undercut key-ways for the plaster at the sides of the flanges.

In the form of product shown in Fig. 5, the flanges 70 are turned outwardly instead 115 of inwardly and there are no continuous lateral ribs.

In the form shown in Fig. 6, the arrangement of openings is the same as in Figs. 4 and 5 but the flanges 72 are turned inwardly 120 and the sides are ribbed as at 73.

In the form shown in Fig. 7, there are only two rows of openings 75, 75' with a single rib 76 extending between the rows of openings longitudinally of the bead. In 125 this case the flanges 77 are turned inward and the flanges 78 are turned outward. This figure also shows a plain folded type of nose 79 in place of the bull nose type of the other figures.

In the form of product shown in Fig. 8 there are four rows of openings in each side with ribs 81 and 81'. The flanges 82, 82' are turned inwardly and the flanges 83, 83' are turned outwardly.

Each of the different forms of product shown has its own advantages. The side toward which the flanges are turned is sometimes more or less rough. For that reason 10 it is desirable to turn the flanges inward where the roughness will not make it unpleasant or difficult to handle the product. By varying the size and arrangement of the 15 openings different effects may be produced rendering the product advantageous under different conditions. The openings in the sides may be formed before, at the same time as, or after the ribs.

Not only is the product itself desirable 20 from the standpoint of strength, and its capacity for keying the cement or plaster, but the type of opening, the flanges and the ribs make it possible to produce it at high speed in a single operation which does not 25 require the attendance of skilled labor or much expenditure for up-keep or loss of time in repairs.

What I claim is:—

1. The process of forming corner bead, 30 which consists in slitting a sheet metal strip at opposite sides of the median line thereof, opening the said slits and turning the metal at some of the edges of the openings at an angle to the general plane of the strip to 35 thereby reinforce the strip and then folding the slit and reinforced strip substantially along the median line into a nose or head portion leaving the sides diverging therefrom substantially as described.

40 2. A continuous process for the manufacture of corner bead, which comprises first slitting a sheet metal strip at opposite sides of the median line thereof, then opening the slits so formed and turning the metal at 45 some of the edges of the openings at an angle to the general plane of the strip, then ribbing the strip longitudinally between the openings therein and finally folding the strip substantially along the median line 50 thereof into a nose or head portion and sides diverging therefrom.

55 3. The process of forming corner bead, which consists in forming openings in a sheet metal strip along opposite sides of the median line thereof, applying a narrow covering ribbon to the central portion of the corner bead strip, forcing the edges of the narrow covering ribbon down into the openings and bending such edges in under the 60 corner bead strip and then folding the corner bead strip and attached covering ribbon substantially along the median line into a covered nose or head portion with sides diverging therefrom.

65 4. The process of forming corner bead,

which consists in forming openings in a sheet metal strip along opposite sides of the median line thereof, applying a narrow covering ribbon to the central portion of the corner bead strip, rolling the edges of the narrow covering ribbon down through said openings and in beneath the corner bead strip and then folding the corner bead strip and attached covering ribbon substantially along the median line into a covered nose 75 portion and sides diverging therefrom.

5. The process of making corner beads, which comprises loosely securing the edges of a non-corrosive strip to a metallic stock and then folding the stock along its central 80 portion and drawing the strip smooth and tight around the folded edge.

6. The process of making corner beads, which comprises perforating metallic stock, forcing portions of a non-corrosive strip into 85 said recesses and then folding the stock and stretching the strip across the folded edge.

7. The process of making corner beads, which comprises securing the edges of a thin non-corrosive strip, in locking engagement 90 with a heavier stock and then folding said stock and strip so as to provide the stock with a protected edge.

8. The process of making corner beads, which comprises first applying a protective 95 coating to the metallic stock, then applying a relatively narrow strip of non-corrosive metal to that part of the stock which is to form the body of the bead and then bending the stock to form the body and the attaching arms.

9. The process of forming corner beads, which comprises securing a protecting strip to the center of a relatively heavier body strip, folding the two strips and stretching the protecting strip across the edge of the heavier body strip and then indenting the 105 sides of the body strip.

10. In a corner bead machine, means for 110 slitting the edge portions of a sheet metal strip, means for opening the said slits and turning the metal at the edges thereof at an angle to the plane of the strip and means for folding the strip into a nose with the edge portions aforesaid diverging therefrom.

11. In a corner bead machine, the combination of rolls for slitting a sheet metal strip, hole opening rolls engaging in the slits so formed and means for progressively 115 bending the strip with the opened slits into a nose and side portions diverging therefrom.

12. In a corner bead machine, the combination of rolls for feeding a sheet metal strip, means for slitting the sheet advanced 120 by the feed rolls, means for opening the slits so formed and means for progressively bending the strip into a nose with side portions diverging therefrom.

13. In a machine for continuously form-

ing corner bead, rolls for continuously feeding a sheet metal strip, slitting rolls arranged to operate on the strip advanced by the feeding rolls, hole opening rolls engaging in the slits so formed and means for progressively bending the strip into a nose and sides diverging therefrom.

14. In a machine for continuously forming corner bead, rolls for continuously feeding a sheet metal strip, slitting rolls arranged to operate on the strip advanced by the feeding rolls, hole opening rolls engaging in the slits so formed and rolls for progressively shaping the strip passing therebetween into a nose and sides diverging therefrom.

15. In a corner bead machine, means for slitting a sheet metal strip, combined slit opening and rib forming means arranged to operate on the slitted strip and means for folding the ribbed and slitted strip into a nose and sides diverging therefrom.

16. In a corner bead machine, slitting rolls arranged to slit a sheet metal strip, combined slit opening and rib forming rolls arranged to operate on the slitted strip and means for bending the strip into a nose and sides diverging therefrom.

17. In a corner bead machine, the combination with means for forming openings in a strip of sheet metal and bead forming means for folding the strip into a bead and divergent sides, of means located between said opening forming means and said bead forming means for applying a protective ribbon to the bead portion of the strip.

18. In a machine for making corner bead

from a sheet metal strip, the combination with opening forming means and bead forming means, of means interposed between the opening forming means and the bead forming means for interlocking portions of a protective ribbon in the openings formed in the strip.

19. In a machine for making corner bead from a sheet metal strip, the combination with opening forming means and bead forming means, of tucking rolls interposed between the opening forming means and the bead forming means for tucking edge portions of a protective ribbon into the openings formed in the strip.

20. In a machine for making corner bead from a sheet metal strip, the combination with opening forming means and bead forming means, of tucking rolls interposed between the opening forming means and the bead forming means for tucking edge portions of a protective ribbon into the openings formed in the strip and folding means arranged to bend the tucked portions of the ribbon into engagement beneath the strip.

21. The process for making corner bead from a sheet metal strip which consists in guiding and rolling edges of the metal strip to smooth the same, forming openings in the strip on opposite sides of the center line, bending the strip adjacent the center line to form a nose portion and flaring the sides and rear edges outwardly.
